UNITED STATES PATENT OFFICE.

JESSE A. CRANDALL, OF BROOKLYN, NEW YORK, ASSIGNOR TO OSCAR REIFFARTH, OF NEW YORK, N. Y.

GARMENT-SUPPORTER.

SPECIFICATION forming part of Letters Patent No. 738,775, dated September 15, 1903.

Application filed August 28, 1902. Serial No. 121,330. (No model.)

To all whom it may concern:

Be it known that I, JESSE A. CRANDALL, a citizen of the United States, residing in New York, borough of Brooklyn, in the State of New York, have invented certain new and useful Improvements in Garment-Supporters, of which the following is a specification.

This invention relates to garment and hose supporters; and the object of the invention is to provide an improved attaching device by which the supporter is attached to the garment.

The invention consists of an attaching device for garment-supporters comprising a flat base-plate having an opening at its rear end for receiving a suitable tape, upwardly-projecting overhanging lugs at its front end, forming a converging socket parallel with the length of said base-plate, and a tongue member having a flat tongue at its front end converging in conformity with said socket and having an offset rear portion disposed substantially parallel with the tongue, said rear portion being provided with an opening for receiving a suitable tape, said tongue member being adapted to be inserted in said socket with its tongue parallel on the base-plate and its rear offset portion extending outwardly from the same, as will be more fully described hereinafter and finally pointed out in the claims.

In the accompanying drawings, Figure 1 is a plan view of a garment-supporter provided with a pair of my improved attaching devices. Fig. 2 shows the attaching device applied to a garment to be supported—as, for instance, a stocking. Fig. 3 is a side view of the attaching device and connected parts of the supporter, the tongue of the attaching device being in this figure removed from the socket. Fig. 4 is a similar side view with the tongue of the attaching device in its socket and the garment indicated in dotted lines; and Fig. 5 is a horizontal section on line 5—5, Fig. 2.

Similar letters of reference indicate corresponding parts.

Referring to the drawings, *e* indicates the base-plate of my improved attaching device or clasp. At its forward portion said base-

plate is provided with two upwardly-projecting overhanging curved grip-lugs or ears. These grip-lugs or ears *ff* are arranged opposite each other and are rounded over at their interior rear corners *f'*, so that the garment inserted between the same is not torn. The base-plate is provided at its rear portion with an opening *e'* for permitting the attachment of a strip *b* of the garment-supporter.

j indicates a tongue adapted to fit into the socket formed by the upwardly-extending grip-lugs or ears and is provided at its rear portion with a suitable opening *j'* for attaching a tape *k* of the garment-supporter. The tongue is made of such size as to fit loosely within the socket formed by the upwardly-extending lugs or ears *ff*. The grip-lugs or ears *ff* are preferably arranged at an angle to each other, and not parallel, so as to form thereby a socket tapering toward the forward end of the base-plate, and the tongue is also preferably tapered. The overhanging portions of the ears *f* also converge toward the opposed or back portion of the base-plate, as shown clearly in Figs. 3 and 4, so as to produce the tight wedging of the fabric between the tongue and said parts. The rear portion *j* of the tongue is preferably arranged at an angle to the forward portion or tongue proper, so as to extend outward from the base-plate *e* when the tongue is inserted into the socket, so as to be conveniently grasped by the user when attaching the device to the garment or removing the same therefrom.

When it is desired to attach the garment-supporter to the garment *m*, the base-plate is placed at the under side of the garment and the tongue then placed upon the outside of the garment in proper position for entering the socket and is then pushed forward into the same. By this operation the garment is drawn in a fold into the socket, as indicated clearly in Fig. 2. Owing to the curved rear portions *f'* of the grip-lugs the garment is readily drawn into the socket and enters the same with the tongue without being in any wise torn or injured. The tongue is pressed in as far as desired and the garment is thereby tightly held between the tongue and base-plate. The continual pull of use only serves to

to draw the tongue farther into the socket, thereby tightening the grip of the attaching device upon the garment. For permitting this drawing in the tape or band *k* is preferably made of such length as to remain loose, as indicated in Fig. 4, even when the tongue is inserted to its greatest extent.

It is obvious that my improved attaching device may be employed in connection with 10 any suitable form of garment - supporter. The garment - supporter shown in the drawings is composed of a main supporting-tape *a*, having a safety-pin *c* attached to the upper end of the same and two tapes *b* attached to 15 the lower end, to each of which is secured one of my improved attaching devices.

My improved attaching device is adapted to receive material of widely - differing character and thickness. It holds securely and 20 without injury the thinnest and most delicate fabrics as well as extremely thick and heavy goods, and possesses the great advantage, owing to the wedge-action between the tongue and grip-lugs, of holding the fabric more securely with each increase in the strain upon 25 the same.

Having thus described my invention, I claim as new and desire to secure by Letters Patent—

30 1. In a garment-supporter, a clasp formed of a wedge-shaped tongue, and a base-plate

adapted to receive said tongue, and having a double taper, substantially as set forth.

2. In a garment-supporter, a clasp formed of a base-plate having upwardly - projecting 35 overhanging side edges converging toward each other and toward the opposed or back portion of the base-plate, and a tongue adapted to be inserted between said converging side edges for wedging a garment between the 40 same and the tongue, substantially as set forth.

3. In a garment-supporter, a clasp consisting of a flat base-plate provided with an opening at its rear end for receiving a suitable 45 tape and upwardly - projecting overhanging lugs or ears at its front portion, said lugs forming a socket the sides of which converge toward each other and toward the opposed or back portion of the base-plate, and a wedge- 50 shaped tongue adapted to be inserted into said socket for securing the garment, said tongue having an offset rear portion provided with an opening for receiving a suitable tape, substantially as set forth.

In testimony that I claim the foregoing as my invention I have signed my name in presence of two subscribing witnesses.

JESSE A. CRANDALL.
